United States Patent

Des. 236,756
Patented Sept. 9, 1975

236,756

SUBMERSIBLE PUMP

Ingemar Franzen, Pforzheim, Germany, assignor to
ITT Industries, Inc., New York, N.Y.

Filed Feb. 14, 1974, Ser. No. 442,368

Claims priority, application Sweden Aug. 16, 1973

Term of patent 14 years

Int. Cl. D15—02

U.S. Cl. D65—1 R

FIG. 1

FIG. 2

FIG. 3

FIG. 1 is a front perspective view of a submersible pump embodying my new design;

FIG. 2 is a side perspective view thereof; and

FIG. 3 is a bottom plan view thereof.

The electric cable has been shown as broken away in FIGS. 1 and 2 for convenience of illustration only.

I claim:

The ornamental design for a submersible pump, substantially as shown and described.
